UNITED STATES PATENT OFFICE

KIRWAN MESSICK, OF CLARENDON, VIRGINIA

EXCAVATOR

Application filed August 26, 1931. Serial No. 559,532.

The present invention relates to excavating machinery of the type now commonly used, employing a truck having a power plant arranged thereupon, which is utilized not only for driving the tractor mechanism of the truck, but also for driving and hoisting the excavating implement thereof, having among its principal desiderata the provision of such an excavator capable of being selectively converted into any of the prevailing types such as dipper shovel, clamshell, skimmer-scoop, drag line excavator, or which may be converted into a pile driver, derrick or crane by simply attaching to the truck the type of boom required.

Another and equally important object of the present invention is to provide a mechanically operable drive capable of being permanently mounted upon a boom of an excavator so that upon attaching the boom to the excavator's tractor truck, the power plant arranged upon the latter may be utilized for driving such mechanically operable drive, thereby keeping the cab of the truck clear of the usual reversible drive mechanism which not only reduces the amount of space required in the cab of the tractor truck, but also materially reduces the cost of building such tractor trucks.

A still further object of the present invention is to provide a reversible crowd or thrust mechanism capable of being permanently attached to the boom of an excavator, thereby not only eliminating the complicated and expensive reversing mechanism usually required within the cab of such tractor trucks for driving the shipper shaft, but permitting a power plant of reduced horsepower to be utilized, thereby not only reducing the cost of manufacture of such excavating machinery, but materially reducing the cost of maintenance.

A still further object of the present invention is to provide a reversible planetary mechanism capable of being permanently attached and carried by the boom of an excavator and

allowing a speed reduction in order that greater force may be obtained from a small power plant when a crowding or thrusting operation is desired, and one which is capable of being speeded up when retracting or lifting the excavating implement from its work, and further, such a planetary reversible drive in which even distribution of stresses to the gearing thereof may be effected during the crowding operation, thereby increasing its durability, stability and a more even and uniform transmission of drive power.

A still further object of the present invention is to provide a power plant for excavators having a three speed drum drive for the drag lines and hoisting cables of such machines whereby not only a reduced amount of cable is required but establishing a drive for such drag lines or cables in order that the excavator may be operated at a slow rate of speed to obtain the maximum power and operated at a faster rate of speed when only the minimum amount of power is required.

The excavating machine embodying the present invention and as herein shown comprises a tractor truck with a power plant mounted in the cab thereof and a boom to which is connected the usual dipper shovel excavator. This boom may be readily replaced with other booms when a different type of excavating implement is required, or the machine may be converted into a crane, pile driver, or derrick by substituting the required boom for the one as herein shown. This power plant arranged upon the tractor truck not only requires two power driven shafts, one of which has operatively connected thereto the cable of the boom hoist, whereas the other drive shaft has connected thereto not only the cable of the shovel or other implement hoist, but has suitable connections for driving the reversible crowd or thrust mechanism of the shovel or other excavating implement employed. From this arrangement, it is quite obvious that but few

working parts are required within the cab of the tractor truck, thereby not only keeping the cab clear of machinery which is not at all times needed, but materially reduces the 5 cost of manufacture of such tractor trucks.

The reversible crowd or thrusting mechanism usually required for excavating machines is herein mounted upon the boom of the excavator and arranged about the shipper 10 shaft thereof, whereby this shipper shaft may be driven in opposite directions only and by mechanically controlling this reversible drive mechanism, the dipper stick and its shovel may be caused to travel in reverse directions 15 as is needed when crowding the dipper within the work or withdrawing the same from the work. Whereas it is quite common in this particular art to arrange reversible motors upon the booms of excavators or to drive the 20 shipper shaft arranged upon the boom from a reversible drive mechanism arranged in the cab of the excavator, I believe that I am the first to provide a mechanical reversing mechanism upon the booms of excavators and which 25 can be driven from a power plant arranged within the tractor truck thereof and capable of being manually controlled by the operator seated within the cab of such tractor truck. It is also quite common in this particular art 30 to arrange a reversible crowd mechanism of the planetary type within the cab of a tractor truck and drive the shipper shaft arranged upon the boom in opposite directions, but by arranging such reversible crowd mechanism 35 of the planetary type upon the boom of an excavator permits the power plant and tractor truck thereof to be converted into other types of excavating machines than of the dipper shovel type as herein shown, by simply disconnecting the drive to the reversible crowd 40 mechanism arranged upon the boom and also substituting the boom of the required excavator for the one herein shown.

In order that the invention and its mode 45 of operation may be readily understood by persons skilled in the art, I have in the accompanying illustrative drawings and in the detailed following description based thereon, set out several possible embodiments of the 50 same.

In these drawings:

Figure 1 is a side elevation of a power driven excavator employing the outside dipper stick and having one form of my invention 55 applied thereto;

Figure 2 is a plan view of the same;

Figure 3 is a side elevation of an excavator employing the inside dipper stick and also having another form of the invention applied 60 thereto;

Figure 4 is a detail side elevation of a boom with the inside dipper stick applied thereto and showing the shipper shaft of the crowd mechanism journaled within the boom;

65 Figure 5 is another detail side elevation

of the boom showing an electric motor mounted upon the boom for driving the crowd reversing mechanism;

Figure 6 is a detail transverse sectional view taken through the boom as is illustrated 70 in Figure 3 of the drawings, and showing my improved crowd reversing mechanism mounted upon the boom;

Figure 7 is a detail sectional view through my crowd reversing mechanism as applied 75 to the boom;

Figure 8 is a detail side elevation of the boom with my crowd reversing mechanism mounted thereon;

Figure 9 is a detail sectional view taken 80 through the crowd reversing mechanism, as is shown in Figure 1 of the drawings, wherein an outside dipper stick is employed, and

Figure 10 is a detail perspective view of 85 one of the idler gears and its mounting.

Referring now more particularly to the accompanying drawings wherein like corresponding parts are designated by similar reference characters throughout the several views, I have herein shown a truck 1 which is preferably propelled over the ground by means of a tractor mechanism, a conventional form of which is herein shown and indicated by the numeral 2. Mounted upon and adapted to revolve upon the truck 1 is a 90 cab comprising a platform 3 and hingedly connected to the forward end of this platform is a boom 4. The hinge connection 24 between the boom 4 and the platform 3 of the cab is preferably of a detachable construction wherein the shovel boom as herein shown may be easily and readily removed in order that other types of booms may be connected thereto and the machine selectively converted into other types of excavators such as skimmer-scoops, trench hoes, clamshells, and the like, or the machine may be employed as a crane, derrick or pile driver.

In Figures 1, 2 and 9 of the drawings, I have illustrated an outside dipper stick carried by the boom 4 in that this dipper stick is forked so as to straddle the boom 4. Connected to the lower end of the dipper stick in any preferred or well known manner is a dipper shovel 7 carrying a sheave 8 over which passes the shovel hoisting cable 9. The reversible crowd mechanism herein generally indicated by the numeral 10 is mounted upon the boom 4 and is employed for directing the shovel 7 to and from the work.

Mounted upon the platform 3 of the cab is a prime mover preferably of the internal combustion engine type and herein indicated by the numeral 11, which, through the gearing 12, drives a shaft 13. This shaft 13 has suitably connected thereto a drum (not shown) to which is connected the cable 14 of the boom hoist. This cable 14 has one end connected to the outer end of the boom 4 and after extending over a pulley 15 carried by 125

the framework arranged upon the platform 3 of the cab passes over the pulley 16 and 16' and the opposite end of the cable 14 is attached to the drum mounted upon the shaft 13, whereby when this shaft is set in motion the boom 6 may be raised or lowered to the desired position. Another shaft 17 is journaled in suitable bearings upon the platform 3 of the cab and is also driven through the gearing 12 by the motor 11 in order that this shaft 17 may revolve in one direction. Loosely mounted upon this shaft 17 is a small drum 18 as well as a larger drum 19 and the opposite ends of the cable 9 are connected to these drums. Suitable clutches 20 are employed for establishing a means whereby these drums 18 and 19 may be selectively connected to the shaft 17 in order that they will be caused to rotate with this shaft 17 and these clutches 20 are controlled by the foot pedals 21 arranged adjacent the operator's seat 22. As the ends of the cable 9 of the dipper shovel hoist are connected to these drums 18 and 19, the medial portion of the cable passes over the sheaves 23 arranged at the fair-lead end of the boom 4, and the sheaves 8 of the shovel. When the drum 18 is operatively connected to the driven shaft 17, the cable 9 will be caused to wind thereupon and as the opposite end of this cable is fixed to the drum 17 which remains stationary, the shovel 7 will be lifted at the lower rate of speed, which is preferable when heavy work is being done. By operatively connecting the larger drum 19 to this driven shaft 17, the cable 9 will be caused to wind thereupon and as the opposite end of this cable is fixed to the drum 18, which is then held against rotation, the dipper shovel will be raised at a faster or second rate of speed which is preferable when lighter work is being performed. When it is desired to raise this dipper shovel at a greater rate of speed, for instance, where it has been released from the earth in which it has been digging, the drums 18 and 19 may be jointly connected to the shaft 17 through their respective clutch mechanisms 20 whereupon both ends of the cable 9 will be wound thereupon and the shovel 7 raised at a much increased rate of speed.

This driven shaft 17 has also keyed or otherwise connected thereto, a sprocket wheel over which passes a sprocket chain 24 and this latter passes over another sprocket wheel secured to the shaft 25 which latter is preferably journaled in bearings arranged at the pivot point of connection between the boom 4 and the platform 3. This driven shaft 25 is provided with another sprocket wheel over which travels a sprocket chain 25' and the latter passing over a sprocket wheel carried by the shipper shaft of the crowd reversing mechanism 10 arranged upon the boom 4 in order that with rotation of the driven shaft 17 the sprocket chain 25' which is connected to the

shipper shaft of the crowd mechanism arranged upon the boom will travel in one direction only.

When employing the outside dipper stick as is illustrated in Figures 1, 2 and 9 of the drawings, the drive connection between the drive shaft 17 and the crowd reversing mechanism is arranged within the boom 4 but when employing inside dipper stick as shown in Figures 3 and 6 of the drawings, the sprocket wheel 26 is connected to one side of this drive shaft 17 and a double sprocket wheel 27 is journaled upon a suitable stub shaft arranged at one side of the boom 4 whereby the sprocket chains 24 and 25' may pass thereover for establishing a drive connection between this drive shaft 17 and the reversible crowd mechanism 10.

In Figures 1 and 3 of the drawings, this reversible crowd mechanism 10 is shown as being arranged upon the boom 4 but it may be preferable to arrange this reversible crowd mechanism within the boom 4 so that its shipper shaft will be journaled within the side members of the boom in the manner as is illustrated in Figure 4 of the drawings.

Referring now to Figures 6, 7 and 8 of the drawings wherein I have shown in detail a reversible crowd mechanism as mounted upon a boom employing an inside dipper stick. Seated upon the faces of the spaced and parallelly arranged bars 28 of the boom and connected thereto by means of the bolts 29, are bearing brackets 30 and journaled within the bearings 31 of these brackets 30 is a sleeve 32. Formed with this sleeve 32 are the gears 33 which latter are adapted to mesh with the rack bars 34 formed with or carried by one face of the dipper stick 6 whereby with rotation of this sleeve the dipper stick may be raised or lowered. Loosely mounted upon this sleeve 32 and arranged between the gears 33 is a bearing sleeve 35 having formed therewith a projecting block 36 which latter is arranged between the side bars of the dipper stick 6 and connected to the outer end of this block 36 by means of a bolt 37 is a cross plate 38 which latter holds the rack teeth 34 of this dipper stick in mesh with the gears 33. Journaled within and extending through this sleeve 32 is a shipper shaft 39 and also keyed to one projecting end of this shipper shaft 39 is a sprocket wheel 40 over the latter of which passes a sprocket chain 25' in order that with rotation of the driven shaft 17 arranged within the cab of this machine, this shipper shaft 39 will be caused to revolve in one direction only. Formed with one end of the sleeve 32 is a drum 41 and adapted to be brought into engagement with this drum 41 is an inner brake band 42 and an outer brake band 43. This inner brake band 42 is supported and carried by the sprocket wheel 40 so as to rotate therewith and when this brake band 42 is expanded as to engage the drum 41,

120
125
130

this drum, together with the sleeve 32 will be caused to revolve with the sprocket wheel 40. The other brake band 43 is carried and fixedly secured to, as at 44, one of the side members 28 of the boom 4 in order that when this brake band 43 is forced into engagement with the drum 41, the sleeve 32 will be held stationary.

The opposite end of this sleeve 32 is provided with another drum 45 having internally arranged gear teeth 46 and meshing with this internal gear 46 are a pair of idler gears 47, the latter meshing with a larger gear 48 keyed to the shipper shaft 39. The gear wheels 47 are carried by a drum 49 which extends over the drum 45 and this drum 49 is provided with a hub 50 which latter is loosely mounted upon one of the projecting ends of the shaft 39. Supported by and connected to the other side member 28 of the boom 4 is a brake band 51 which latter is adapted to engage the drum 49 in order that the gears 47 may, at times, be retained against rotation around the gear 48, and in this manner effect a reverse drive between the gear 48 keyed to the shaft 39 and the internal gear 46 which is carried by the sleeve 32. The connection between the brake bands 43 and 51 consists of the levers 52 pivotally supported upon the bearing block and are provided with the usual eccentric connections between the opposite ends of these brake bands in order that the latter may be brought into and out of engagement with their respective drums. Rods 53 are connected to these levers 52 and these rods 53 are controlled by a suitable foot lever 54 arranged within the cab of the machine. The gears 47 are each mounted upon a shaft 54' which latter is arranged within a suitable bearing block 56, as is better illustrated in Figure 10 of the drawings. This bearing block 56 has formed therewith, a plate 55 and the bearing block fits within an opening formed in the plate 49, whereas the plates 55 are secured by means of bolts 57 to this plate 49.

From the construction herein set forth, it is quite obvious that I have provided a reversible crowd mechanism which is arranged solely upon the boom 4 of the machine and is driven by the power plant within the cab of the machine whereupon with rotation of the shipper shaft 39 of this reversible drive mechanism in one direction, a shovel 7 may be thrust or crowded within the works by simply operating the brake band 51. The gear connection between the shaft 39 and sleeve 32 is such as will provide a two to one ratio between the driven shaft 39 and this sleeve 32, whereby with a small amount of power an increased thrust may be given to the shovel 7 than where a direct drive is effected between such a shipper shaft 39 and the dipper shovel 6. When withdrawing this dipper stick 7 from the work, it is preferable that the withdrawing operation be done

at a greater rate of speed and the operator, by causing the brake band 42 to be brought into engagement with the drum 41 of the sleeve 32, a direct drive is established between the prime mover and the dipper stick, whereupon the latter will be caused to be withdrawn from the work in a rapid manner. When it is desired to hold the dipper stick 6 stationary at any desired position, the operator positioned within the cab may actuate the brake band 43 thereby locking the drum 41 and the sleeve 32 to the boom 4.

Whereas I have herein shown the brake bands 43 and 51 as being capable of manual operation by the operator within the cab of the machine it is, of course, to be understood that other means well known in the art may be so employed. Instead of showing a manually operative means for controlling the brake band 42, I have herein illustrated how this brake band may be operated under fluid pressure. Within the cylinder 58 carried by the sprocket wheel 40 is a piston, which is connected to the brake band 42 through the link connection 59. The shipper shaft 39 is provided with a passageway 60 having communicating with one end thereof the interior of the cylinder 58 whereas the opposite end of this passageway 60 is connected with a fluid supply pipe 61. This fluid supply pipe 61 should extend within the cab of the machine and have a suitable valve arranged therein, whereby the operator upon opening such valve would permit the fluid to pass through this pipe 61 into the cylinder 58 whereby the brake band 42 may be expanded and caused to engage the drum 41.

In Figure 9 of the drawings, I have illustrated my reversible crowd mechanism as carried upon the boom 4 of an excavator wherein an outside dipper stick is employed. In this form of the invention, the drive chain 25 which moves in one direction passes over a sprocket wheel 62 and the latter is journaled upon the shipper shaft 63. This shaft 63 is mounted within suitable bearings 64 carried by the side members 65 of the boom 4 and gear wheels 66 are secured to this shaft 63, which mesh with the rack bars 67 carried by the opposite side members of the dipper stick 6. These rack bars 67 of the dipper stick are retained in mesh with the gears 66 by means of the bracket arms 68 mounted upon the opposite end of the shaft 63. The hub of the sprocket 62 has formed therewith a large gear 69 and fixedly secured to the shaft 63 is a plate 70 formed with internal gear teeth which mesh with the intermediate gears 71 and the latter also mesh with the larger gear wheel 69. The intermediate gears 71 are carried by a drum 72 loosely mounted upon the hub of the gear 69 and adapted to engage this drum 72 is a brake band 73 whereby when this drum 72 is retained against rotation, the shaft 63 will be

caused to revolve in a direction opposite to a sprocket wheel 62 at a reduced rate of speed, whereby the dipper stick of the shovel will be forced outwardly or towards the work.

5 When withdrawing the dipper 7 from the work, the brake band 74 is brought into operation whereby the drum 75 carried by the shaft 63 will be directly connected to the sprocket wheel 62 due to the fact that this

10 brake band 74 is attached to a plate 76 carried by the sprocket wheel 62. Another brake band 77 carried by one of the side members 65 of the boom may also be brought into engagement with the drum 75 whereupon the shaft 63 may remain stationary and the dipper held at the desired position.

When it is desired to mount a motor upon the boom 4 and employ my reversible crowd mechanism it may be done in the manner as 20 illustrated in Figure 5 wherein I have shown an electric motor 78 having a small gear wheel 79 carried by the armature shaft thereof of which latter is adapted to engage a large gear wheel 80 of the shipper shafts 39 or 63 25 of the reversible crowd mechanism. From this construction, it is obvious that upon setting the motor 78 into motion, the gear 80 will be caused to revolve in one direction whereupon the operator seated within the cab of the machine may control the brake band of 30 this reversible crowd mechanism as hereinbefore described, in order that the dipper and its dipper stick may be caused to travel in opposite directions or be retained in the desired stationary position upon the boom.

An excavator made in accordance with my invention can be driven from a power plant arranged within the cab of a propelled car or truck having a suitable motor such as a gas engine, and two driven shafts therein, similar to the shafts 13 and 17, thereby greatly reducing the amount of space necessary for the installation of such drive mechanism within the cab as well as reducing the cost thereof, due to 40 the elimination of expensive drums and connections with the motor for operating the reversible crowd mechanism of the excavator. I am aware of the fact that reversible crowd mechanism of the planetary gear type has been heretofore used on excavators, which reversing crowd mechanism is installed within the cab, requiring expensive machinery and taking up considerable space therein. I am 50 also aware of the fact that various forms of motors, steam and fluid, have been arranged upon the boom of excavators for giving a reverse motion to the dipper stick, and also chain drive mechanisms connecting the dipper stick with the motor arranged within the cab. However, I believe that I am the first to 60 adopt a mechanical reversing mechanism upon the boom of an excavator, whereupon a dipper stick can be moved in opposite directions. The chain drive between the motor driven mechanism arranged within the cab

and the reversible crowd mechanism is such that the chain 25 will at all times, travel in one direction and the mechanical reversing mechanism will cause the dipper stick to travel in opposite directions thereby materially reducing the size of chain drives necessary, over those heretofore used wherein the chain moves in opposite directions. Also, this mechanical crowd connection between the dipper stick and the drive chain permits the latter to accomplish greater work due to the reduced gear ratio between the shipper shaft of the reversible crowd mechanism and the dipper stick when the latter is being thrust into the work. When withdrawing the dipper from the work, less power is needed, and, therefore, my reversible crowd mechanism may establish a direction between the drive mechanism and the dipper stick for withdrawing the latter from the work rapidly, and with a minimum amount of power.

Wherein I have herein shown a shovel type of excavator as being connected to a portable power plant, other types of excavators such as a trench hoe, skimmer-scoop, clamshell, may be readily connected to this traveling power plant by simply removing the boom 4 and substituting therefor the boom of the type of excavator desired. By arranging the reversible crowd mechanism upon this boom, considerable amount of space may be saved within the cab of the power plant whereby an ordinary power plant may be employed having drums arranged within the cab for connecting the drag line or cable to the other types of excavators which are connected thereto. This same power plant may also be used as a pile driver or frame by attaching the required type of boom thereto.

It will, furthermore, be understood that with a power plant made in accordance with this invention and employing two drums similar to those indicated by the numerals 18 and 19, hoisting cables may be connected thereto for lifting objects at three different rates of speed, one of which is needed when heavy work is being done, the second being employed when lighter work is being done and the third, or faster rate of speed, being used when it is desired to quickly raise an article such as the dipper 7 connected to the cable which winds upon the drums 18 and 19.

In mounting the two drums 18 and 19 upon a single drive shaft and permitting the same to be jointly or selectively connected to such drive shaft, a three speed hoist may be established, not only for shovel excavators as herein shown, but for other excavating machines or hoists which are employed when converting the machine.

Manifestly, the construction herein shown is capable of considerable modification and such modifications as come within the scope

of my claims, I consider within the spirit of my invention.

I claim:—

1. A reversible crowd mechanism for power driven excavators comprising in combination a boom, a dipper stick for reciprocation upon said boom, rack bars secured to said dipper stick, a shipper shaft journaled upon said boom, means for driving said shipper shaft in one direction only, a sleeve loosely mounted upon said shipper shaft, gears fixedly secured to said sleeve and adapted to mesh with said rack bars secured to said dipper stick, drums formed with the opposite ends of said sleeve, means for connecting one of said drums to said shipper shaft whereby said dipper stick will be caused to travel in one direction, and means for connecting the other of said drums to said shipper shaft whereby said dipper stick will be caused to travel in a reverse direction.

2. A reversible crowd mechanism for power driven excavators comprising in combination a boom, a dipper stick mounted for reciprocation within said boom, rack bars secured to said dipper stick, a shipper shaft journaled upon said boom, a sprocket wheel keyed to said shipper shaft whereby the latter may be driven in one direction only, a sleeve loosely mounted upon said shipper shaft, gears formed with said sleeve and adapted to mesh with said rack bars secured to said dipper stick, drums secured to the opposite ends of said sleeve, means for operatively connecting one of said drums to said sprocket wheel whereby said dipper stick will be caused to travel in one direction, and a planetary gearing connecting the other of said drums with said shipper shaft whereby said dipper stick will be caused to travel in a reverse direction.

3. A reversible crowd mechanism for power driven excavators comprising in combination a boom, a dipper stick mounted for reciprocation within said boom, rack bars secured to said dipper stick, a shipper shaft journaled upon said boom and having its opposite ends projecting beyond the opposite sides of the boom, a sprocket wheel keyed to one of the extended ends of said shaft for driving the latter in one direction only, a sleeve journaled upon said shipper shaft, gear wheels formed with said sleeve and adapted to mesh with said rack bars of the dipper stick, drums formed with the opposite ends of said sleeve and arranged on the opposite side of said boom, means whereby one of said drums may at times be connected to said sprocket wheel for causing said sleeve to rotate in one direction, a planetary gearing connecting the other of said drums to said shipper shaft, and means connected to said sleeve whereby said rack bars will be retained in mesh with said gears formed with said sleeve.

4. A reversible crowd mechanism for power driven excavators comprising in combination a boom, said boom consisting of a pair of spaced and parallelly extending bars, a bearing block secured to each of said bars, a dipper stick mounted for reciprocation within the bars of said boom, rack bars secured to said dipper stick, a sleeve journaled within said bearing blocks carried by the bars of said boom, gears formed with said sleeve and adapted to mesh with said rack bars of the dipper stick, a drum formed with each end of said sleeve and said drums extending from the outer side of the bars of said boom, a shipper shaft, and means whereby said shipper shaft may be operatively connected to the drums of said sleeve, substantially as and for the purpose specified.

5. A reversible crowd mechanism for power driven excavators comprising in combination a boom, a pair of bearing blocks secured to said boom, a dipper stick mounted for reciprocation within said boom, rack bars secured to said dipper stick, gears formed with said sleeve and adapted to mesh with said rack bars, a shipper shaft extending through said sleeve and mounted for rotation therein, a drum formed with each end of said sleeve, a sprocket wheel keyed to said shipper shaft and adapted to be driven in one direction only, means for connecting at times one of said drums with said sprocket wheel whereby said dipper stick will be caused to travel in one direction, a drum loosely mounted upon said shipper shaft, planetary gearing for connecting said shipper shaft with the other of said drums formed with said sleeve, and means for holding said drum which is loosely mounted upon said shipper shaft against rotation whereby through said planetary gearing said dipper stick will be caused to move in a reverse direction.

6. A reversible crowd mechanism for power driven excavators comprising in combination a boom, said boom consisting of a pair of spaced and parallelly extending bars, a dipper stick mounted for reciprocation within the bars of said boom, rack bars secured to said dipper stick, bearing blocks secured to the bars of said boom, a sleeve journaled within said bearing blocks, gears formed with said sleeve and adapted to mesh with said rack bars carried by said boom, means supported by said sleeve for holding said rack bars carried by said dipper stick in mesh with the gears formed with said sleeve, a shipper shaft extending through and journaled within said sleeve, a sprocket wheel keyed to said shipper shaft and adapted to rotate in one direction only, a drum formed with said sleeve, means for connecting at times said drum with said sprocket wheel, a brake adapted to engage said drum for holding said sleeve against rotation, an internally arranged gear formed with said sleeve, a gear

wheel keyed to said shipper shaft, a drum loosely mounted upon said shipper shaft, idler gears carried by said drum which is loosely mounted upon said shipper shaft and meshing with the gear wheel keyed to said shipper shaft and the internally arranged gear formed with said sleeve, and means whereby at times said drum having the idler gears supported therein may be held against rotation and said sleeve caused to be rotated in a direction opposite to that of said shipper shaft.

In witness whereof I have hereunto set my hand.

KIRWAN MESSICK.
